UNITED STATES PATENT OFFICE.

LEWIS A. WOBROCK, OF MERTON, MINNESOTA.

APPARATUS FOR COATING RECEPTACLES WITH PARAFFIN.

No. 900,815.

Specification of Letters Patent.

Patented Oct. 13, 1908.

Application filed January 9, 1908. Serial No. 409,918.

To all whom it may concern:

Be it known that I, LEWIS A. WOBROCK, a citizen of the United States, residing at Merton, in the county of Steele and State of Minnesota, have invented certain new and useful Improvements in Apparatus for Coating Receptacles with Paraffin; and I do hereby declare the following to be a full, clear, and exact description of the invention, such as will enable others skilled in the art to which it appertains to make and use the same.

My invention has for its object to provide an improved process of and apparatus for coating butter tubs and various other articles with paraffin, and to this end the process consists of the novel treatment and the apparatus comprises the novel devices and combinations of devices hereinafter described and defined in the claims.

A simple and efficient form of the novel apparatus, by means of which the novel process may be readily carried into effect for coating the interiors of butter tubs and similar articles, is illustrated in the accompanying drawings, wherein like characters indicate like parts throughout the several views.

Referring to the drawings, Figure 1 is a plan view of the apparatus. Fig. 2 is a section taken approximately on the line $x^2 x^2$ of Fig. 1 and showing also in section a butter tub in position to receive an interior coating of paraffin; and Fig. 3 is a section taken on the line $x^3 x^3$ of Fig. 1.

The paraffin, indicated by the character z , is placed in a receptacle, preferably in the form of a conical metal basin 1, secured at its margin to an annular metal rim 2 which, in turn, is shown as supported by suitable legs 3. The basin 1 is provided with radial ribs 4, preferably formed by bending thin sheets of metal into U shape and securing the lower edges thereof, at the ends of the ribs, directly to the concave surface of said basin, leaving clearance passages 4^a between the said basin and the intermediate portions of the said ribs. At the inverted apex or lowest central portion of the basin 1 is a rigidly secured depending neck or sleeve 5,

50 into which, as shown, is screwed a hollow threaded valve casing 6. A steam supply pipe 7 leads from a suitable source of steam supply into the lower end of the valve casing 6. This pipe 7 is preferably provided with a valve 8, by means of which it may be opened and closed so that the steam may be

cut off or supplied in any desired quantities, at will. A gravity seated valve 9 having an upwardly extended stem 9^a and a depending stem 9^b normally closes the passage through the valve casing 6. As shown, the upwardly extended stem 9^a works through the hub of a transverse guide bar 10, shown as secured to the lower end of the sleeve 5, while the depending stem 9^b works through a similar transverse guide bar 11 secured in the valve casing 6.

The character y indicates a wooden butter tub which, as shown in Fig. 2, is inverted and placed with its down-turned rim on the supporting ribs 4, so that it directly overlies the valve 9 and is supported with clearance for the escape of air and steam between the lower edge thereof and the upper portion of the basin 1.

The operation of the apparatus described, in carrying out my improved process, is as follows: The valve 8 being opened more or less, steam under pressure will be forced upward through the body of paraffin z and will vaporize and absorb or become commingled with the vaporized paraffin. The steam laden with paraffin vapors will fill the inverted tub y and, coming into contact with the inner surface thereof, will deposit on said surface a thin layer of paraffin, which latter, upon coming into contact with the tub, condenses and forms a thin coating over the entire inner surface of the tub. Any of the steam that may condense, by the contact with the tub, will run back into the basin 1, or if absorbed by the tub, will later evaporate, leaving the proper thin but evenly distributed coating of paraffin on the inner surface of the tub. The valve 9 will automatically open whenever the steam pressure exceeds the pressure of the atmosphere and of the column of paraffin, which latter is contained in the basin 1, but whenever the steam is cut off or reduced below such pressure, said valve will automatically close, under the action of gravity, and will thereby prevent the molten paraffin from running downward through the valve casing 6 into the steam supply pipe 7.

It will thus be seen that the process consists in coating a tub or other article, by first commingling paraffin vapors with steam and then applying the commingled steam and paraffin vapors to the surface to be coated. The steam also serves as the agent for melting and vaporizing the paraffin, and when the

steam is caused to pass through the molten body of paraffin it absorbs or becomes commingled with the vaporized paraffin.

In actual practice the improved process 5 has been carried out in a most satisfactory manner by the novel apparatus above described. It may, however, be performed by apparatus of other form of construction.

What I claim is:

- 10 1. In an apparatus for coating butter tubs and other articles with paraffin, the combination with a basin, of a steam supply pipe leading into the bottom of said basin, and a check valve in the vicinity of the bottom of 15 said basin normally closing the steam passage thereto but adapted to be opened by steam pressure, substantially as described.

2. In an apparatus for coating butter tubs and other articles with paraffin, the combination with a basin adapted to contain a 26 body of paraffin and provided with radial tub-supporting ribs, of a steam supply pipe opening centrally into the bottom of said basin, and a check valve located in the vicinity of the bottom of said basin normally 25 closing the steam supply passage thereto and adapted to be opened by steam pressure, substantially as described.

In testimony whereof I affix my signature in presence of two witnesses.

LEWIS A. WOB BROCK.
